UNITED STATES PATENT OFFICE

CLINTON A. DETWILER, OF PALMYRA, PENNSYLVANIA, ASSIGNOR TO JOHN G. DOUPLE AND HENRY S. REAM, OF PALMYRA, PENNSYLVANIA.

FOLDING IRONING-TABLE.

No. 923,117. A Notified Specification of Letters Patent.

Patented May 25, 1909.

Application filed April 27, 1908. Serial No. 429,440.

To all whom it may concern:

Be it known that I, CLINTON A. DETWILER, a citizen of the United States, residing at Palmyra, in the county of Lebanon and State of Pennsylvania, have invented certain new and useful Improvements in Folding Ironing-Tables; and I do declare the following to be a full, clear, and exact description of the invention, such as will enable others skilled in the art to which it appertains to make and use the same.

My invention relates to ironing tables, and particularly to that type which are foldable or collapsible so as to occupy small space when not in use.

The object of the invention is the provision of a device of this character which may be conveniently and expeditiously folded into a small space, and which will be properly supported when extended or set up for operation.

A further object of the invention is the provision of means which enables me to properly support the board, and, at the same time, turn it out of the way of one of the supports so that a skirt or circular garment may be placed thereupon.

A still further object is the provision of a device of this character which will have its bracing means so positioned as to avoid interference with the work.

With these and other objects in view, the invention consists of certain novel features of construction, combination and arrangement of parts as will be described and particularly pointed out in the appended claims.

In the accompanying drawing, Figure 1 is a perspective view of the device ready for operation; Fig. 2 is a longitudinal sectional view thereof; and Fig. 3 is a side elevation of the table shown in folded position.

Referring more especially to the drawings, 1 and 2 represent foot pieces or supports, from which extend the vertical supports, 3 and 4, connected together by cross pieces, 5 and 6, or any other suitable manner which may be deemed desirable. The parts thus described form the rear support for the board, and hinged to the lower cross bar, 5, adjacent its center, is a bracing rod, 7, which is hinged at its opposite end to an upright, 8, carried by the foot piece or support, 9. The upper end of the standard or support 8 is provided with a cross arm, 10, which is mortised in the outer face of the

support 8 for a purpose which will herein-after be described. Adjacent the supports, 3 and 4, and connected to the cross pieces, 5 and 6, is a pair of U-shaped guide rods, 11 and 12, both of which have their ends passing through apertures in the cross pieces and secured thereto in any suitable manner.

The board which is indicated at 13, is provided with a cleat, 14, at its rear end, which is pivotally connected to the board by a bolt, 15, which runs therethrough. This cleat is provided on its underside with eyes, 16, which engage the rods, 11 and 12, so as to prevent any rotary motion of the cleat, and to permit the cleat and the board to work up and down there-over, when it is desired to fold the board. The forward end of the board is provided with a batten, 18, which is notched at 19 to receive the end 20 of the standard, 8, and be engaged on its outer side by the cross arm, 10.

In Fig. 3 it is clearly shown how the device is folded. The board is raised to vertical and slid downwardly on the rods and is held in place by a U-shaped retaining bail, 21, which has its ends secured in the uprights, 3 and 4. The support 8 is brought inwardly toward its connecting bar, 7, and both are folded upwardly alongside the cross braces, 5 and 6, the support 8 being inserted between the cross piece 6 and the board 13.

When the table is in the position shown in Fig. 1 and ready for operation, the board may be raised from the support 8 and turned upon its pivot bolt, 15, so as to place a skirt or other circular garment thereover in position to be ironed.

From the foregoing description, taken in connection with the accompanying drawing, the construction and operation of the invention will be readily understood without requiring a more extended explanation.

Various changes in the form, proportion and the minor details of construction may be resorted to without departing from the spirit or sacrificing any of the advantages of the invention as defined in the appended claims.

Having thus described my invention, what I claim as new and desire to secure by Letters-Patent, is:

1. In a device of the class described, the combination with a vertical support, of a pair of separated guide members carried by said

support, a cleat having eyes surrounding said guide members so as to be adaptable for reciprocation thereon, a board pivotally connected to said cleat for lateral movement, and a second support for the opposite end of the board.

2. In a device of the class described, the combination with a vertical support, of a pair of separated guide members carried by said support, a cleat having eyes surrounding said guide members so as to be adaptable for reciprocation thereon, a board piv-

otally connected to said cleat for lateral movement, and a second support foldably connected with said first-mentioned support 15 and adapted to support the free end of the board.

In testimony whereof I have hereunto set my hand in presence of two subscribing witnesses.

CLINTON A. DETWILER.
